BAG CLEANING MACHINE

Leo Burwick and Joseph J. Springer, Buffalo, N. Y., assignors to Carl Burwick & Company, a partnership composed of Carl Burwick, Hyman Burwick, Israel Burwick, and Leo Burwick

Application November 4, 1943, Serial No. 508,926

6 Claims. (Cl. 223—43)

This invention relates to bag cleaning machines, particularly of the type using air suction for removing particles from the bags.

Objects of the invention include the provision of a continuously operating automatic machine having means rendering the same capable of clamping bags in series, moving the bags into operative location relative to an air suction device so that the bag is projected into the device for the initial cleaning step, at the same time the bag being thereby turned inside out; while still clamped the bag is advanced and the bag clamp is rotated 180 degrees to position the inverted bag in a location to be acted upon by a second air suction device which performs the final cleaning operation and again reverses the bag to its original condition; the clamp being then again rotated 180 degrees to bring it to original position, and clean, the bag then being discharged and the bag clamp advancing to the original loading position, thus completing the cycle.

Further objects of the invention include the provision of a continuously operating automatic bag cleaning machine which is so constructed that the only action necessary on the part of the operator is to insert the open end of the bag in a holder which automatically clamps the bag in open position; the provision of a bag cleaning machine as aforesaid comprising a rotating platform on which are mounted a plurality of rotatable shafts in general radial relation thereto, each shaft being provided at its outer end with automatic clamping means for holding the bag in position for the cleaning operation with the bag held open; in combination with means such as a mutilated gear for intermittently rotating the shaft, that is, subsequent to an initial cleaning step wherein the bag is reversed and again rotating the shaft after a second cleaning operation which also inverts the bag so that the latter will be discharged from the machine in its original condition but having been air cleaned.

Further objects and advantages of the invention will appear hereinafter, reference being had to the accompanying drawings, in which:

Fig. 1 is a plan view of the machine embodying the invention;

Fig. 2 is a view in elevation showing the parts advanced approximately 45 degrees from the position of Fig. 1;

Fig. 3 is a view in elevation showing the machine at a different period of operation;

Fig. 4 shows a bag in a holder during the second rotation thereof; and

Fig. 5 shows the same prior to the initial rotation.

In cleaning bags by air suction it has been heretofore the practice to arrange a vertical air pipe or conduit having its lower end open at a

distance of approximately four feet from the floor. The operator picks up a bag and holds it by its open end under the opening in the pipe, whereupon the air suction will invert the bag and draw it up into the pipe to an extent limited by the operator; the operator then pulls the inverted bag down out of the pipe and repeats the operation so as to clean the bag twice, once for each side, and this results in returning the bag to its original position after the cleaning has been accomplished. The present invention provides a machine for accomplishing the above stated action mechanically and automatically with no labor to be performed except in initially positioning the bag in the machine.

A generally vertically arranged housing 10 is provided, this housing being supported on the floor or on some other support and in the present instance being shown as cylindrical. Centrally of housing 10 and supported by any convenient means therein there is a vertical shaft 12 which may be driven at a relatively slow speed by any desired means. A platform 14 is mounted on shaft 12 to rotate therewith as by means of a bracket 16 or other convenient device. Supported from the housing 10 in fixed relation thereto and surrounding shaft 12 there is a mutilated gear 18 having gear teeth 20 and 22, the remainder of the gear being blank.

30 A number of substantially radial shafts are mounted in bearings 24 on platform 14 to rotate therewith. In the present instance, four of these shafts indicated at 26, 28, 30 and 32, are shown, but it is to be understood that any number of shafts may be employed. Each of the shafts is provided with a pinion gear 34 fixed thereto for a purpose to be described, and at its outermost end each shaft is provided with a circular collar as at 36. Collars 36 are fast to the respective shafts for rotation therewith.

Each shaft is also provided with a fixed lug 38 which pivotally mounts a pair of substantially bell-crank shaped elements 40 which extend outwardly and terminate in curved clamping arms 42 which conform to the shape of the circular collars 36. The lugs 38 are fast to their respective shafts and rotate therewith but are restrained from sliding motion by any desired or convenient means. Each shaft is also provided with a slideable but non-rotatable lug 44 each of which carries a depending pin 46. Lugs 44 are connected to lugs 38 by means of a pair of tension springs 48 for the purpose of normally maintaining the lug 44 in outward radial position on its shaft. 55 Lugs 44 may be moved radially inwardly of the shaft against the tension of springs 48. Each lug 44 is provided with a pair of pivoted levers 50 which in turn are pivoted to the ends of the bell cranks 40. This construction provides that 60 springs 48 will maintain the clamping arms 42 in

clamping relation to the exterior of the respective collars 36 but upon inward radial retraction of lugs 44 the clamping arms 42 will be retracted from collars 36.

Referring to Fig. 2 it will be seen that the platform 14 dependently mounts radial shafts 52, there being a shaft 52 for each of the shafts mounted above the platform. Shafts 52 and their respective operating shafts 26, etc., are parallel and are connected by means of pinions 54 which mesh with gears 34 so that rotation of shafts 52 will rotate their connected shafts and thus will rotate the collars and arms 42 comprising the bag holders. Each shaft 52 is provided at its innermost end with a gear 56 which is arranged to mesh intermittently with the mutilated gear 18 and thus it will be seen that shaft 28 in Fig. 1 will rotate 180 degrees before it assumes the position of shaft 30 and likewise shaft 30 in Fig. 1 will rotate 180 degrees before it assumes the position of shaft 32, so that shafts 26, 28 and 30, in Fig. 1, are so arranged that the pins 46 associated therewith depend, but the pin 46 associated with shaft 30 extends upwardly.

In Fig. 1 the air suction pipes will be arranged directly over the positions shown in Fig. 3 for the bag holders for shafts 28 and 30 and at these two points the two cleaning operations occur. The illustration of Fig. 2 is made with platform 14 having been rotated counter-clockwise, as seen in Fig. 1, a distance of 45 degrees, the air pipe indicated at 60 will be located as shown, and at this point in the rotation of the device no cleaning is being done; whereas in the Fig. 3 showing one of the bags is illustrated as being cleaned.

A cam rod 62 is mounted on the exterior of housing 10 in fixed relation thereon, and this rod is provided with outwardly-extending lips 64, 66. Rod 62 is not concentric with shaft 12 and it is arranged so that depending pins 46 will be engaged by the lip 64 to slightly retract lug 44 to release a bag and as the platform 14 advances in a counterclockwise direction lug 44 will be further retracted to open clamping arms 42 to a greater degree as shown with relation to shaft 26 in Fig. 1.

In Fig. 1 shaft 26 shows the loading position, shaft 28 shows the position of initial cleaning, shaft 30 shows the position for the second cleaning, and shaft 32 shows the discharge position. The operator picks up a bag by its open end and arranges it about collar 36 in position to be clamped by arms 42 as the lip 66 is reached in the progress of the machine. The bag will depend down about the exterior of element 36 as shown at the right in Fig. 2. When the position of shaft 28 is reached the continuously operating air suction apparatus will bring the depending bag upwardly through the circular collar 36 and into the air pipe 60 as illustrated at the right in Fig. 3. This action obviously inverts the bag. As the machine progresses the bag will be withdrawn from the air suction pipe 60 and will trail down over the trailing edge of the holder. From the position of shaft 28 to the position of that at 30 gear 20 will cause shaft 52 to rotate in a direction to rotate the shaft through 180 degrees so that the bag will now hang freely from the holder as originally placed on the machine but inverted. At the position of shaft 30 the bag is again projected up into the second air pipe and reinverted, after which the bag will trail again over the trailing side of the bag holder. From the position of shaft 30 to that of shaft 32, gear 22 will cause a further rotation of the bag holder

through 180 degrees to complete a full turn of 360 degrees and thus bring the bag back to its original position, whereupon it is discharged from the machine as above described. All the operator has to do is to arrange the bags on the collar 36 at the loading station, the rest of the operations being completely automatic.

Any well known friction clamp may be provided to yieldingly hold the shafts 26, 28, 30, or 32 in horizontal position, such device not being shown for purposes of clarity of illustration.

Having thus described our invention and the advantages thereof, we do not wish to be limited to the details herein disclosed, otherwise than as set forth in the claims, but what we claim is:

1. A bag cleaning apparatus comprising a rotary support, a series of radial rotary shafts thereon, a bag clamp in the form of a hoop on each shaft, said support having a loading station and a discharge station, said bag clamps being normally horizontally disposed, a pair of air suction devices beneath which the clamps pass, and means to rotate the shafts and bag clamps a half turn after each air suction device is passed by the clamps.

2. A bag cleaning apparatus comprising a rotary support, means to rotate the support, a series of radial rotatable shafts on the support, a generally hoop-shaped bag holder on each shaft, means associated with each holder to clamp a bag in open-mouth dependent position thereon, a pair of spaced air suction devices in the path of travel of the holders, said suction devices drawing the bags severally through the holders and inverting the bags while cleaning the same, and shaft rotating means to invert the holders.

3. A bag cleaning apparatus comprising a rotary support, means to rotate the support, a series of radial shafts on the support, means to intermittently rotate the shafts, a hoop-shaped bag holder on each shaft, a clamp for each holder, a pair of air cleaning suction devices having operative ranges in the path of the holders as the support rotates, said shaft rotating means alternating with the suction devices in the direction of movement of the support.

4. Apparatus of the class described comprising a support, a bag clamp in hollow form for clamping a bag in open dependent condition thereon, means to invert the bag, means to invert the bag clamp, and a second bag inverting device to reinvert the bag and a second bag clamp inverting means.

5. Apparatus of the class described comprising a support, a bag clamp in hollow form for clamping a bag in open dependent condition thereon, means to invert the bag, means to invert the bag clamp, a second bag inverting device to reinvert the bag, a second bag clamp inverting means, and means to free the bag from the clamp.

6. A bag cleaning apparatus comprising a series of bag clamps, means to move the clamps in a closed path, a pair of spaced air suction cleaning devices adjacent said path to act on the bags severally to clean and invert the same, bag clamp inverting means located to rotate the clamps between the air suction devices, and a second bag clamp inverting means acting subsequent to the second cleaning and inverting device.
